CLAIM

The ornamental design for a fishing reel cap, as shown and described.

DESCRIPTION

FIG. 1 is a perspective view of a fishing reel cap;
FIG. 2 is a top perspective view thereof;
FIG. 3 is a bottom perspective view thereof;
FIG. 4 is a left side elevational view thereof, the right side being a mirror image;
FIG. 5 is a front elevational view thereof; and,
FIG. 6 is a rear elevational view thereof.
The broken lines shown in the drawing views are included for the purpose of showing environmental structure that forms no part of the claimed design.
